UNITED STATES PATENT OFFICE.

EDWARD L. WILLIAMS, OF KENOSHA, WISCONSIN.

DESIGN FOR A BICYCLE-LAMP.

SPECIFICATION forming part of Design No. 30,150, dated February 7, 1899.

Application filed December 10, 1898. Serial No. 698,915. Term of patent 7 years.

To all whom it may concern:

Be it known that I, EDWARD L. WILLIAMS, a citizen of the United States, residing at Kenosha, in the county of Kenosha and State of Wisconsin, have invented and produced a new and original Design for Bicycle-Lamps, of which the following is a specification, reference being had to the accompanying drawings, in which—

10 Figure 1 is a plan view of a bicycle-lamp embodying my design; Fig. 2, a front elevation; Fig. 3, a plan section taken on the line 3 3 of Fig. 2; Fig. 4, a side elevation; Fig. 5, a rear elevation, and Fig. 6 a cross-section taken on the line 6 6 of Fig. 2.

15 The leading feature of my design, as shown in the drawings, consists in the generally spheroidal conformation of the several parts of the lamp, comprising the upper portion of 20 the body or flame-chamber, the lower portion or generating-chamber, and the rear portion or water-reservoir, which is located back of the flame-chamber and has its contiguous portion recessed or reentrant, so as to conform 25 approximately to the general spherical contour of said flame-chamber.

20 Referring to the drawings, 10 indicates the body of the lamp, which is spherical in its general contour, having openings at its top and bottom and also at the front and on both sides. Around the opening at the top is located an upwardly and outwardly flaring collar 11, above which is supported a cap 12, having a central portion which is shaped like 25 a segment of a sphere, while its marginal portion is in the form of a flat annulus. The opening at the front is surrounded by an outwardly-flaring reflector 13, having the shape of a frustum of a cone, and is closed by a lens 30 14. The openings at the sides of the body

are provided with the usual glass side lights or lenses 15, which are approximately segments of a sphere in shape, their outer surfaces being faceted, as shown.

35 The water-reservoir 16 is located back of the lamp-body or flame-chamber and has the general shape of an oblate spheroid, its front portion adjacent to the rear of the body of the lamp being reentrant, as indicated at 17, so as to conform to the generally spherical 50 projecting body of the lamp.

40 The lower portion of the lamp or generating-chamber 18 is also spheroidal in shape, being flattened on its underside and connected with the flame-chamber 10 by an intermediate portion 19, which is circumferentially grooved and ribbed to produce an ornamental effect. The tube 20 extends diametrically across the intermediate portion 19 and then at an angle 55 in the same horizontal plane to a point under 60 the water-reservoir, to which it is connected by an upwardly-extending portion 21.

45 I have shown the top or cap 12 as provided with a surface ornamentation of a conventional six-pointed star, while the back of the 65 reservoir is shown as ornamented with a conventional figure of the sun. The flame-chamber of the lamp and the upper part of the intermediate portion 19 have openings therethrough, as shown, and the body of the generating-chamber has an equatorial band of vertical ribs or projections.

50 I claim—

55 The design for a bicycle-lamp, substantially as herein shown and described.

60 EDWARD L. WILLIAMS.

Witnesses:

65 FREDERICK C. GOODWIN,
IRVINE MILLER.
